UNITED STATES PATENT OFFICE.

EDGAR EARLE LITTLEFIELD, OF LOS ANGELES, CALIFORNIA.

MEANS FOR CONTROLLING ELECTRIC CURRENTS.

Original application filed July 19, 1916, Serial No. 110,053. Divided and this application filed January 5, 1922. Serial No. 527,204.

This application is a division of an application filed by me on the 19th day of July, 1916, Serial #110,053, for an improvement in methods of intermittently operating apparatus, which application has resulted in Patent Number 1,404,155, issued January 17, 1922.

My invention relates to means for controlling electric currents carried by conductors which are adapted to be bridged by fluids. It further relates to means of controlling currents in circuits by variations caused in the specific gravity of the fluid bridged in the circuits. As a specific example of an application of my invention I have employed the current carried by a circuit to develop a gaseous fluid which I have employed, by suitable means, to force away from contact with each other a conducting liquid and an electrode which forms one of the terminals of a gap between which the fluid is interposed. It will be clear that with my method the gas formed by the chemical reaction of the current may be interposed as a resistance between the terminals to thereby open the circuit. It is obvious that in the operation of any apparatus wherein it is desirable to automatically open a circuit through electro-chemical reaction this method may be employed.

Obviously, my invention provides a means for automatically interrupting a flow of current when the same is undesirable or unnecessary.

With the above objects in view I have shown and described typical means for carrying out and applying the invention and have defined the same in the claims terminating this specification, it being understood that the invention is susceptible to a variety of different modifications without departing from the spirit of the claims.

In Figure 1 I have shown one type of construction embodying my invention, the same comprising a urinal, shown partly in vertical sections.

In Figure 2 I have shown a longitudinal section through a plug-like member which may be used as a terminal connection for the apparatus employed.

Figure 3 is a modified trap-like member which may, if desired, be substituted for the trap shown in Figure 1.

In the various views like numerals refer to like elements.

In my aforesaid patent, I have shown and described typical means for carrying out the present invention, which patent, by reference, is made a part hereof. For the present purpose, however, my invention will be understood by reference to the accompanying drawings, which show the invention as employed in connection with an intermittently operated apparatus.

In Figure 1 is shown a urinal of a type which is controlled by an electric circuit the terminals of which are adapted to be bridged by the flushing fluid. This figure also shows the trap of the fixture partly broken away and the device of Figure 2 in assembled relation.

As explained hereinafter, it is obvious that when the flushing fluid is slightly impure, or when, for any reason, it is desirable to automatically open the circuit, the gas formed by the chemical reaction of the current may be interposed as a resistance between the terminals.

In Figure 2 I have shown a detail view of the electrode 9, of Figure 1. This electrode, or terminal, resembles an ordinary spark plug, except that no spark gap is provided and the insulating member 27 forms a tube within which is closely fitted the cylindrical carbon electrode 7. For this carbon electrode may be substituted any other acid resisting conductor, such as either of the metals platinum or tungsten. In Fig. 2 the plug member 9 is shown partly in cross section. The lower free end 8 of electrode 7 is provided with a convex surface upon which the gas of polarization is deposited. In any apparatus employing my method, I contemplate that any suitable form of electrode, or its associated parts, may be used, whether specifically set out herein or not. It is evident that when sufficient gas has been deposited to cover this surface, the circuit will be automatically opened.

Instead of using the form of electrode shown in Figure 2 I may use such a construction as that shown in Figure 3, in which is shown a modified form of trap, partly broken away. In this form an upturned bend in the trap pipe forms a chamber 12 within which a gaseous medium may accumulate and displace any fluid contained therein. In the upper part of this chamber an opening is provided for the plug member 9 which is removably secured by 110

means of screw threads which permit of any desired adjustment. Since in this case the bend in the pipe, together with the plug member 9, form a chamber within which the 5 gaseous medium may accumulate the lower free end of electrode 7, as well as the lower end of the insulating member 27, are provided with plane surfaces instead of the recessed surface shown in Fig. 2. Obviously 10 the trap pipe may be formed of conductive material, as described hereinafter, in which case it may form one of the electrodes or terminals of the circuit the other or companion electrode or terminal being provided 15 by aforesaid plug member 9. When substituted for the trap shown in Figure 1 and properly connected up the modified structure may be employed to interrupt the flow of current in the manner described. In this 20 case the gas resulting from the chemical reaction rises in the chamber 12 surrounding the lower free end of the electrode 7, forcing the trap fluid away from contact with the electrode and automatically opening the 25 circuit. Upon re-establishing contact between electrode 7 and the trap fluid, as by adding fluid to the trap, the circuit will again be completed. Obviously either the 30 immersed surface of the electrodes or their distance apart may be varied.

The device of Figure 1 shows my invention embodied in a plumbing fixture. The present method may be understood by a consideration of its mode of operation. 35 One terminal of a controlling circuit 25 is connected at 28 to the metal waste pipe 10, while another terminal is connected to the plug member 9 of the trap of a urinal bowl. 1. A source of current is indicated at 6. 40 The flushing fluid is supplied by supply pipe 3, while its flow is controlled by the electrically-operated valve 4, which is controlled by circuit 25. As will be seen the electrodes or terminals 7 and 10 are spaced from each other but in a position to be bridged by the 45 flushing fluid. Upon the introduction of such a conducting fluid as urine between the terminals of circuit 25 the valve 4 will operate to cause a flushing of the fixture. But if the flushing fluid is slightly impure a 50 leakage of current would occur, for the terminals or electrodes are normally bridged by the flushing fluid. Upon the passage of the current, however, a gas is developed 55 which it is one of the objects of the present invention to employ to open the circuit. Any suitable means may be employed to effect this result.

I have found that the invention is applicable for controlling either a direct or alternating current although, for obvious reasons, the action is more prompt with the former.

There are many forms of apparatus in 65 which my method may be employed.

From a consideration of the foregoing it will be clear that the invention provides, in one of its phases, a method for controlling, or operating, apparatus through the medium of changes in the electrical condition of a circuit caused by variations in the character, or condition, of a fluid which forms a link in said circuit.

I claim:

1. A flushing system having controlling 75 means including an electric circuit; companion electrodes for said circuit one of which is located in the upper wall of a pocket normally containing liquid; means whereby the collection of a fluid adjacent the latter electrode will force the liquid away from the the electrode and break the circuit.

2. In combination; an energy transforming device adapted to perform useful work; a controlling circuit in series therewith; 85 means for introducing a liquid resistance into the path of said circuit, said circuit having an electrode arranged to function in a fixed position; means for trapping an elastic fluid adjacent said electrode in such 90 a manner as to utilize the pressure of said fluid to force said liquid away from contact with said electrode.

3. A flushing system for urinals and the like including; a source of liquid; a valve 95 therefor; controlling means for said valve including an electric circuit and means for substituting an elastic electrically nonconductive fluid for a liquid electrical conductor forming a resistance in said circuit to thereby interrupt a flow of current in said circuit, said elastic fluid acting to force said liquid conductor out of the path of said circuit.

4. In a flushing system for urinals and the like; the combination of a receptacle adapted to receive waste, having a discharge conduit and provided with a flushing means including an electrically controlled valve; with an electric circuit including the electrically controlled valve and having insulated terminals 100 spaced in the discharge conduit to be bridged by liquid contained in the conduit, whereby current passing through the bridging liquid tends to generate gas from susceptible matter carried by the liquid; and means for collecting the gas around one of the terminals to displace the liquid at said terminal to introduce a resistance gap in the circuit to interrupt the flow of current in said circuit.

5. In a flushing system for urinals and the like; the combination of a receptacle adapted to receive waste, having a discharge conduit and provided with a flushing means including an electrically controlled valve; with an electric circuit including the electrically controlled valve and having insulated terminals 125 spaced in the discharge conduit to be bridged by liquid contained in the conduit, whereby current passing through the bridging liquid tends to generate gas 130

from susceptible matter carried by the liquid; and means providing a chamber open to the conduit and surrounding one of the terminals to collect gas from the conduit 5 around said terminal to introduce a resistance gap in the circuit to interrupt the flow of current in said circuit, the entrance of additional liquid into the conduit operating to flush the gas from the open chamber to 10 restore the bridging contact of the liquid contained in the conduit.

6. In a flushing system for urinals and the like; the combination of a receptacle adapted to receive waste, having a discharge conduit 15 and provided with a flushing means including an electrically controlled valve; with an electric circuit including the electrically controlled valve and having terminals spaced in the discharge conduit to be bridged by liquid

contained in the conduit, whereby current 20 passing through the bridging liquid tends to generate gas from susceptible matter carried by the liquid; and an insulating sleeve for one of the terminals having a concave end at the extremity of the terminal open 25 to the conduit, said concave end serving to collect gas generated at the enclosed terminal to introduce a resistance gap in the circuit, said concave end being positioned with relation to the conduit whereby additional 30 liquid entering the conduit tends to clear the gas from the terminal to restore the bridging contact of the liquid contained in the conduit.

In testimony whereof I have hereunto affixed my signature at Los Angeles, California, this 29th day of December, 1921.

EDGAR EARLE LITTLEFIELD.
